United States Patent

Des. 240,745
Patented July 27, 1976

240,745

ANTHROPOMORPHIC FIGURE

Dorese E. Thulin, 2412 2nd St.,
Santa Monica, Calif. 90405

Filed Dec. 6, 1974, Ser. No. 530,203

Term of patent 14 years

Int. Cl. D21—01

U.S. Cl. D34—4 R

Fig. 3.

Fig. 2.

Fig. 1.

FIG. 1 is a front elevational view of an anthropomorphic figure showing my new design;

FIG. 2 is a left side elevational view thereof; and

FIG. 3 is a rear elevational view thereof.

The side not shown is similar to the side shown.

I claim:

The ornamental design for an anthropomorphic figure, as shown and described.
